United States Patent Office

Des. 225,642
Patented Dec. 26, 1972

225,642

ORTHODONTIC CABINET

Ransom M. Westover, 4130 Baywood Drive SE.,
Grand Rapids, Mich. 49501

Filed Oct. 1, 1971, Ser. No. 185,930

Term of patent 14 years

Int. Cl. D24—01

U.S. Cl. D24—1

FIG. 1.

FIG. 3

FIG. 4.

FIG. 2.

FIG. 5.

FIG. 1 is a side-elevational view of an orthodontic cabinet showing my new design;

FIG. 2 is a side-elevational view thereof taken from the side opposite to that shown in FIG. 1;

FIG. 3 is an end elevation thereof;

FIG. 4 is an end elevation thereof taken from the end opposite to that shown in FIG. 3; and

FIG. 5 is a top plan view thereof.

I claim:

The ornamental design for a orthodontic cabinet, substantially as shown and described.
